LUBRICANT DISTRIBUTING SYSTEM

Joseph Bijur, New York, N. Y., assignor, by
mesne assignments, to Auto Research Corporation,
a corporation of Delaware

Application September 12, 1923
Serial No. 662,195

41 Claims. (Cl. 184—7)

My present invention relates primarily to lubricating installations of the type in which lubricant pressure is transmitted from a pressure source, such as a pump, through a system of 5 lubricant filled piping, concurrently to various distributed outlets therein, which communicate with the bearings.

The invention relates especially to systems of the above type from which the escape of oil 10 is precluded while the pressure source is idle and particularly where special instrumentalities assure correct distribution of the charge between the various bearings or groups of bearings.

15 In a preferred installation, the lubricating oil is forced through small metal pipes by the pressure applied at the source, for delivery to the bearings in parallel. The flow controlling instrumentalities are disposed in the path of flow to the 20 bearings and comprise highly restricted outlets which I call "drip plugs" preferably associated or combined, each with a valve, which may be pressed by a spring against its seat, to maintain the line full at all times. It is found that the 25 valves of the drip plugs will close satisfactorily when seated by springs, that retract under about 5 pounds of oil-pressure to permit normal flow. To avoid exacting requirements of manufacture, a variation of one or even two pounds each way 30 may be allowed, so that a normal valve might open anywhere between say 3 and 7 pounds. The outlet of each drip plug is restricted to such extent as to offer an obstruction to the flow of lubricant several times greater than the resistance to flow encountered in the length of the 35 pipes, added to that imposed by the valves particularly when spring seated.

In this case when pressures substantially higher than the valve seating pressures, say of the 40 order of 30 to 50 pounds are applied to the line, the valves will open substantially concurrently and the drip plugs will determine the flow to each bearing substantially regardless of substantial difference in the lengths of the courses from the 45 pump to the various drip plugs.

It is undesirable to utilize lubricant pressures of the order of the valve seating pressures, as for example of 5 or 10 pounds, since this would result in great inequalities in the flow from the 50 drip plugs, as those nearest the pump outlet or having the lightest valve springs would open first and permit the oil to escape and perhaps prevent the pressure building up at all to the point where the stiffer or more remote valves would 55 operate, whereby the distribution would be faulty.

To assure reliable distribution at all times in a system of the type considered, it is, therefore, important to apply the high pressure to the line initially at each operation and to substantially maintain it during operation. A spring 60 discharged pump would be suitable for this purpose, provided too much of the energy is not wasted within the pump, and provided the pressure transmitting agency intervening between the pump and the outlets is substantially incompressible at all times. Only in this case would the discharge pressure of the pump promptly 65 raise the line pressure to maximum, for concurrent opening of all the valves and for correct distribution through the drip plugs of an oil 70 charge equal to that forced into the line by the pump. The pump piston would settle slowly as lubricant is slowly forced through the drip plugs. Rapid settling of the piston would here be a dependable signal, showing either that the oil reservoir was empty or that the line was fractured or broken, the latter condition becoming evident 75 from a pool of oil under the break.

If, however, any part of the system connecting the pump discharge to the drip plugs should 80 distend or dilate to too great an extent under the normal operating pressure of the oil, or if large quantities of air should be trapped in the pipe system at such place where it could not readily escape, the efficacy of the system would 85 be impaired. In such case, the introduction of oil from the pump into the line would result merely in compressing the trapped air volume to a certain extent accompanied with a slight increase in the line pressure. Repeated operation of the pump may be necessary to raise the pressure sufficiently to effect escape of oil from the lightest drip plugs, or from those nearest the pump, and thereafter the oil would continue 90 to escape in an irregular manner until the pressure had again receded to normal, so that a great excess of oil would pass to some bearings, and little or none to others.

In a system so impaired, even though the reservoir were quite full of oil and the pipe line intact, 100 the pump piston would ordinarily settle rapidly rather than slowly, and this rapid action of the piston would provide no indication as to the condition of charge of the reservoir or of damage to the line.

In originally setting into service, an empty or new installation, which has no closed region of relatively large cross-section, where substantial quantities of air might readily be trapped, the 105 pump is operated repeatedly, to charge the line 110

with lubricant, the air quickly escaping through the drip plugs as the oil advances in the pipes, until the latter are completely filled with oil.

Even though substantially all air be satisfactorily excluded by initially charging the pipe system completely with oil, quantities of air might subsequently be trapped in the line, with the objections previously noted. This would occur in the absence of special precautions, if the level of oil in the reservoir which supplies the pump becomes so low that the pump draws air rather than oil, and might tend to force such air into the pipe system.

It is accordingly an object of the invention to provide a system of the above type, easily and reliably operable as long as the parts of the system are uninjured, to deliver predetermined charges of oil from a reservoir, simultaneously to a multiplicity of distributed bearings, by a single simple non-selective operation.

Another object is to provide a system of the type mentioned in which even if the pump should be operated one or more times with little or no lubricant in the cylinder thereof, the subsequent operation after the reservoir has been replenished shall nevertheless be as regular and as satisfactory as at the outset.

Another object is to accomplish the result last stated without substantial increase in the cost, complexity or bulk of the system, and without loss or impairment of any of the other advantages that may inhere in the system to which the invention is applied.

Another object is to provide a system of the above type, including a pump, the friction loss of which is low at all times, so that energy manually applied, is efficiently converted into high line pressure.

Another object is to provide a lubricating system, which, without special alarm devices, registers or the like, will inherently indicate when the supply of lubricant should be replenished.

According to my invention means is provided to function when the pump or pressure generator is operated without lubricant in the cylinder thereof, to prevent the generation of air pressure in the line, and preferably by relieving, venting or expelling from the system through a course other than through the outlets which lead to the bearings, any air in the range of operation of the pump, said air-relieving or venting means being constructed and arranged to sustain pressure applied thereto through the more viscous lubricant. My installation thus operates selectively to vent air and to transmit pressure through lubricant.

The air exclusion device may be provided either in advance of the pump discharge to prevent the entry of the air even to the head of the line or alternatively in the line, and preferably in such place or places therein where any admitted air would naturally become trapped for ready escape thereof, when pressure is subsequently applied.

The air exclusion device in one embodiment is a valve near the head of the line and held closed by the pressure exerted upon the lubricant in the pump discharge to insure transmission of lubricant pressure through the pipe system, said valve remaining in its normal unseated position as long as the pump operates upon air rather than lubricant.

Another type of device performing the function of allowing ready escape of air and yet sustaining pressure transmitted through lubricant, is a highly restricted outlet, for instance, the crevice which would result by substantially filling a metal bore

of about $\frac{1}{16}$ " in diameter, with a rod in the neighborhood of .004 inch smaller in diameter. The minute crevice outlet is sufficiently large to allow any trapped air to be ejected therethrough by oil from the pump, while the much more viscous lubricating oil would drip therethrough but slowly, even under the substantial pressure generated in the pump, and, therefore, without any appreciable relief of pressure.

Other objects and features of the invention will appear hereinafter.

In the preferred embodiment of pump, the operating means therefor, protrudes from above the highest level of lubricant, so that no stuffing box is required whose friction would increase the hand pull and reduce the oil pressure applied to the line.

In the accompanying drawings in which are shown one or more of various possible embodiments of the several features of the invention,

Fig. 14 is a longitudinal sectional view thereof taken along the line 14—14 of Fig. 13.

Referring now to Fig. 1 of the drawings, I have indicated diagrammatically a combined reservoir and pump *p* preferably upon the front of the dashboard 10, to which it is secured by a strap 11, about the reservoir, which is bolted to the dash.

The reservoir and pump unit which is shown in detail in Figs. 2 to 5, and will be described fully below, has a discharge outlet 12, which supplies the various bearings on the chassis through a line, preferably a metal pipe system, a fragment of which is indicated diagrammatically in Fig. 1.

The system includes a main run 13 extending lengthwise within the channel frame of the vehicle and having taps *t* (only one of which is shown) to the various bearings. Fittings of the type shown in Fig. 10 are preferably used to control the supply to the various bearings, each fitting being applied either at or in advance of the corresponding bearing.

Each said fitting includes a relief valve 14 normally seated as by a spring 15 to prevent leakage of lubricant from the line and a metal stem 16 fits into a bore in the neighborhood of .004" larger in diameter to provide a minute crevice which affords resistance to flow much greater than the resistance in the length of the pipe system, so

that the fitting alone for any given lubricant pressure, practically determines the rate of lubricant discharge to the bearing. The general type of flow rate-controlling fitting shown is designated

"drip plug" and need not be here described in detail.

greater detail, as taken by itself it is no part of the invention claimed in the present application, but is fully described and claimed in my copending applications, Serial Nos. 580,668, filed Aug. 9, 1922, 5 and 654,606, filed July 30, 1923.

To assure delivery of clean oil to the bearings, so as to avoid deranging the drip plugs by the deposit therein of dirt carried by the oil, I may provide a special filter F in the line through which 10 the oil from the pump is forced on its way to the bearings. This filter is here shown in the form of a junction box of dimensions such as to fit inobtrusively within one of the channel frames 17 (see Fig. 7) said filter comprising a casing 18 with 15 integral support lugs 19 bolted to the channel frame and having an inlet nipple 20 connected by a length of pipe 21 with the pump discharge 12 and having one or more outlet nipples, three being shown at 22, 23 and 24 by way of illustration. 20 to supply respectively, concurrently and in parallel, the front shackle, 25, the steering gear 26 and the main 13. The filter is shown apart and in detail in Figs. 8 and 9 and will be described more fully below.

25 In the assembly shown, the pump is operated from a pull handle 27 extending through a bracket 28 bolted as at 29 to extend below the instrument board 30, said handle transmitting its tension through a wire 31, which extends through 30 aperture 10' in the dashboard to a sheave wheel 32 on the pump, to which it is secured by a screw 33. The handle is shown apart in Fig. 6 and will be described fully below.

35 *The lubricant and pressure source*

The embodiment shown in Figs. 2 to 5 includes a sheet metal cylindrical oil reservoir having a bottom 34 telescoped over the lower edge of the side wall 35 and a cover 36 telescoped over the 40 upper edge thereof. The cover has a neck 37 near one side thereof, over which is telescoped a collar 38 for the filling opening cover 39, said collar having a bead 40 by which the rim 41 of a strainer bag 42 is clamped against the top of the neck, 45 through an interposed wire lock w. The strainer bag may be of fine copper wire mesh or, if desired, of cloth, and intercepts any relatively coarse particles carried with the lubricant. The cover is preferably of the hinged type and consequently 50 will not collect dirt as would a removable cover that might be placed on a dirty surface, while the reservoir is being filled. In the specific embodiment shown, the cover cap has an upturned hinge loop 43 encircling a hinged pin 44 mounted in eyes 45 formed at the ends of a wire 46 encircling the collar 38 and fitting into the bead 40, the cover being preferably provided with an integral spring-metal tab 47 to snap over the wire 46. The cover cap includes a corrugated spacer disk 48 therein, 55 with a vellumoid or equivalent seating disk 49 thereunder, both secured to the cap 39 by means of a rivet 50, which may also pass through a name plate 51 superposed over the cover. The corrugations on the spacer disk 48 are perforated as at 60 52, as is the vellumoid disk at 53, to maintain the reservoir vented by air passing between the collar 38 and the spaced flange 39' of the cover rim and through the perforations in the spacer and seating disks.

65 The pump cylinder 54 extends longitudinally of the reservoir near one side thereof, laterally of the strainer 42 and protrudes as at 55 well below the bottom of the reservoir. The cylinder is positioned in the reservoir by a pilot 56, which depends from the cover and over which the upper

end of the cylinder is telescoped, and a split metal ring 57 about the cylinder is snapped into a corresponding groove 58 in the bottom of the reservoir. Preferably the ring 57, cylinder 54 and reservoir bottom 34 are soldered together into 80 a uniform leak-proof construction.

In the preferred embodiment, the bottom of the cylinder 54 is closed by a metal plug 59 locked thereinto by a split metal ring 60. The plug 59 has an upstanding valve seat 61 normally closed by a valve V urged thereagainst by pressure transmitted through spring 63 upon the piston 64. An outlet fitting 12 is connected to the plug 59 by a union nut 65 and the supply line 21 is soldered or brazed to said fitting. If desired, a check valve 66 may be used, urged upward by a coil spring 67 against a valve seat 68 formed in the bore 69 of the plug, said spring reacting against a perforated sheet metal cap 70 friction-fitted into the lowerend of the bore 69. The piston comprises a hollow shank 71 of relatively large diameter, upset at its lower end to form a seat 72 for the valve V during the down stroke. The piston head preferably comprises a metal cap 73 with its flange extending upward and a leather cap 74 having its flange 90 extending downward, both clamped against the upset seat 72 by a nut 75 encircling the shank. It is preferred also to clamp between the seat 72 and the cap 74 a sheet metal valve cage member 76. The cage-bottom 77 which is press-fitted into 95 the cage wall 76 has a central opening 78 through which the seat member 61 protrudes in the lowermost position of the piston. The valve V in the present embodiment comprises a sheet metal disk 79 having a plurality of spaced depending lugs 100 about its periphery, a pair of disks 81 and 82 which may be of vellumoid upon opposite faces of the metal disk being secured to the latter by means of a central rivet 83 therethrough. In the position shown in Fig. 2, the lugs 80 are spaced above 105 the bottom 77 of the valve cage, so that during the upward stroke of the piston, the valve will be supported by its lugs 80 upon the bottom of the cage, allowing free passage of lubricant through the piston.

110 The discharge spring 63, to be more fully described below, presses at its lower end against the nut 75 and reacts at its upper end against a stop ring 84 firmly wedged and retained by means of a split locking ring 85 within the upper ends 115 of cylinder 54.

120 The operating shaft 86 is journalled within a hood 87 which is secured to the cover, above the cylinder 54 by rivets 88 passing through hood flange 89 and also serving to secure the pilot 130 member 56. The bearings for shaft 86 comprise an inwardly extending sheet metal hub 90 having flanges 91 riveted to the hood, and a similar hub 94 protruding outward through a corresponding aperture 93 in the wall of the hood and riveted thereto at integral flanges 92. The sheave wheel 32 is forced over the knurled outer end 95 of the shaft 86. A press-fitted collar 96 is fitted over the hub member 94 and a second collar member 97 is fitted over the sheave wheel 32, 140 the flanges 96' and 97' of said collars interfitting to prevent easy entry of dust into the pump. The hood is closed by a cap 98 which may be press-fitted thereover.

145 The shaft is surrounded by a collar 99 extending between the bearings 90 and 94 and a screw 100 extending diametrically through the sleeve and the shaft serves as an anchor for the cable 101 which is connected at its lower end to the piston shank 71. Preferably the cable is a single 150

endless loop straddling the screw 100 and maintained against slipping out from under the screw-head by a sheet metal cup 102, through which the screw 100 extends and which partly encircles the loop of the cable and is pressed against the sleeve 99 by the head of said screw. The lower end of the loop 101 passes about a pin 103 rigidly held within a thimble 104, said pin fitting at opposite ends in holes 105 through the shank of the piston. It is preferred to offset the hood 87 eccentrically with respect to the cylinder, so that the point of tangency of the length of cable 101 with respect to the sleeve 99 will be the axial plane of the cylinder, as best shown in Fig. 3, whereby the pulling strain upon the piston will be axially of the cylinder, avoiding the wear and jamming of the piston, which might result from any substantial lateral force.

It is desirable to provide in addition to the strainer 42, a filter 106 within the reservoir to intercept finer solid particles that may pass through the strainer. This filter is a pad of felt a small distance above the bottom of the reservoir, constituting in effect, a false bottom through which lubricant thereabove will seep to fill the space therebelow. The periphery of the filter pad 106 may be clamped against the in-turned flange 107 of a ring 108 by means of the flange 109 of an inner ring 110 friction-fitted thereto. The filter assembly is secured into the reservoir by friction-fit of outer ring 108 thereto. The pad 106, of course, is apertured to clear the cylinder 54 and is preferably sustained or supported about the cylinder by a ring 111 sustained upon the in-turned rim 112 of the reservoir bottom, and has a flange 113 at its upper end engaging the lower surface of the filter pad, and a split ring 114 fitting into a corresponding groove in the cylinder above the filter pad clamps the latter down against the flange 113 through an interposed spring washer 115.

The filter pad is preferably sustained against sagging in the substantial area thereof between the support rings 110 and 111 by an open structure which may be a band 116 of flexible metal wound in appropriate open convolutions, best shown in Fig. 4, about the cylinder and within the reservoir, said band having preferably scallops or notches 118 at the lower edge thereof.

The cylinder is provided with inlet apertures 119 at the portion thereof between the reservoir bottom 34 and the filter 106, so that only lubricant which has previously seeped into the chamber 120 below the filter, that is, lubricant which has previously been filtered, can enter the cylinder 54.

Preferably the spring 63 even in the most distended position thereof, indicated in Fig. 2 is under relatively high compression. It follows that in the further compression of the spring, as the plunger is elevated to charge the pump, the compressive force will have increased by the end of the stroke through but a small fraction of the initial or minimum compressive force on the spring.

In a specific embodiment which has been found satisfactory, the spring has 50 turns compressed from its length unstressed of about 15 inches to 5.5 inches in the normal discharged position shown in Fig. 2. The spring turns have a low-pitch relation, leaving a space of but .04" between contiguous convolutions, this space to be entirely closed to form substantially a column spring, when the piston reaches the upper end of a two inch stroke. In this specific form, the

increase in spring compression from the beginning to the end of the stroke, will be only about 20 per cent, so that the increase in tensile force required as the charging stroke progresses will be barely noticeable, and the pressure exerted will not decrease markedly as the discharge stroke progresses. Were the spring initially under but a relatively low tension or compression, the distortion thereof to a maximum at the end of the charging stroke, might involve a multiplication of the stress thereon with consequent multiplication of the force required as the charging stroke progresses, and similar decrease of the force exerted in the discharge.

The operating handle

A desirable form of handle is separately shown in Fig. 6. This handle includes an enclosing tubular casing 121 extending inward from the bracket 28 below the instrument board and threaded into a nipple 122 which is clamped against the bracket by a nut 123 threaded upon the inner end of the nipple and secured by an interposed lock washer 124. Coaxial within the casing 121 is a metal operating tube 125 to the outer end of which the operating knob 27 is threaded and locked, said knob being normally in its innermost position against the bushing 122. The operating tube bears within a bushing 126 of wood or other soft material, the latter 100 pressed by the casing 121 against the inturned flange 127 on the nipple.

Within the operating tube is a slidable plug 128 with a tapered axial opening 129 for anchoring the knotted end 130 of the operating wire 31, which extends to the sheave wheel 32. The taper plug is maintained against escape by a closure cap 131 threaded upon the inner end of the operating tube 125. The inner end of the casing tube has a closure cap 132 with a nipple 133 through which the wire 31 extends, a protective sheath 134 which may be of copper tube, for instance, encircling the operating wire, for its entire free length, between the casing and the sheave wheel, and particularly at that portion of the length thereof likely otherwise to rub or wear against the wall of aperture 10' therefor through the dash. The protective sheath is preferably clamped at its outer end against the 125 correspondingly beveled end 135 of nipple 133 by means of a correspondingly beveled shoulder 136 on nut 137 threaded upon the nipple.

The casing 121 is provided with a stop for limiting the stroke of the handle. This stop, as indicated in the drawings, is the stud end 138 of a screw 139 projecting into the casing through an aperture 121'. Screw 139 extends through a supporting ring 140 which encircles the casing 121 and is locked against said ring by a lock washer 141. Ring 140 is rigidly clamped to the casing by a set screw 142 therethrough. It is preferred to provide the casing 121 with a plurality of openings or similar to opening 121' at different parts of the length thereof, through any 140 of which the stop stud 138 may be extended by shifting the position of ring 140, so as to set the length of the operating handle stroke in accordance with the number of drip plugs on the system, or the total quantity of oil to be delivered 145 to the bearings at each pump discharge.

Operation

The reservoir being charged with lubricant admitted through the filling collar 38, the lubri-

cant will readily pass through the strainer 42 and slowly through the filter pad 106 to fill the chamber 120 therebelow, which is vented through apertures 119 and through the bearing collars 90 and 94 in the hood 87. Lubricant will pass through scallops 118 and through apertures 119 until a common level exists in the reservoir and in the cylinder, as indicated by line $a-a$. As the close spring turns are interposed in the path of entry of oil from the reservoir to the cylinders, apertures 119 are of relatively large area and in sufficient number to obviate any appreciable resistance to the entry of oil. The operation of lubricating the bearings consists merely in grasping the knob 27 and drawing the same outward to its limit, when the cap 131 strikes the stud 138. Thereafter without any further attention on the part of the operator, each of the various bearings on the chassis is correctly lubricated.

By the tension on the operating tube 125, the plug 128 is drawn outward therewith, applying tension to the wire 31 to rotate the sheave wheel 32 and with it the operating shaft 86, causing the cable 101 to wind around said shaft and transmit an axial pull to the piston which is thus raised against the resistance of the spring 63.

In this upward stroke of the piston, the floor 77 of the valve cage 76 will first engage the support lugs 80 of the valve and will then raise the valve which throughout said stroke is maintained below piston seat 72, so that throughout the upward or charging stroke, oil will readily pass through the piston and around the valve to fill the chamber below the piston. Check valve 66 avoids any possible suction on the pipe line during this charging operation, which might occur if the pipe system was not closed at every terminal. If the handle is set for maximum charge of the cylinder, the consecutive turns of the spring 63 will contact at the end of the stroke, and the piston cap 73-74 will cover the inlet apertures 119 in the cylinder. If the handle is set for a lesser charge, the spring convolutions will have a small space between them at the end of the charge and the piston may be wholly or partly below apertures 119.

The construction has substantial mechanical advantage, since a six inch pull on the handle and corresponding rotation of the sheave wheel, effects but a two inch rise of the piston, so that with a tensile force say of 15 pounds, a force of 45 pounds would be applied at the piston. The rotary shaft 86 and sheave wheel of the pump introduce frictional losses in the transmission much smaller than would mechanical linkage or a sliding member, and said shaft being above the highest level of oil in the pump unit, my construction dispenses with the need for sliding stuffing boxes whose friction would increase the hand pull and diminish the pressure transmitted to the line. The dust excluding appliance at shaft 86, as heretofore noted, introduces no friction. Moreover, as heretofore pointed out, the force required to overcome the compression of the spring is substantially uniform throughout the length of the piston stroke, so that the manual effort to charge the pump is not much greater at the end than at the beginning of the stroke.

After the charging operation is thus completed, the expansion of the spring 63 forces the piston downward upon the body of oil confined in the cylinder below apertures 119. By reason of the substantial resistance or viscosity of the oil, the valve V will be forced upward against its seat 72 in the piston, so that the passage through the

piston is closed tight during the operating stroke and the lubricant is thus forced out of the cylinder past valve 66 through the length of the pipe system and in parallel through the various drip plugs to the bearings. The drip plugs offering a high resistance to the flow of lubricant therethrough, the descent of the piston even under the expansion of the highly compressed spring 63 will be relatively slow, as the force is transmitted through the incompressible oil filling the pipe between the pump and the outlets.

In this operation, it will be seen that the maximum effort of the spring is exerted as soon as the operating handle is released, so that the maximum pressure is applied substantially at the outset. As this pressure exceeds many times the resistance of each length of line added to that of the drip plug valve at the outlet end thereof, said valves will open substantially concurrently, regardless of differences in the resistance thereof, and in the lengths of pipe leading thereto, and the pressure will be sustained throughout the discharging operation, since the compression of the spring is not much reduced even at the end of the stroke. The spring is thus effective to discharge the cylinder 55 completely and to seat the piston as shown in Fig. 2.

There being ordinarily a substantial interval between successive operations of the pump, it follows that even when the lubricant in the reservoir is low, sufficient will have seeped through the filter pad 106 in the interval between operations, to fill the cylinder to corresponding level, in the manner previously described. The pump will, therefore, operate effectively almost until the reservoir is completely drained of lubricant.

Were any part of the pipe system between the pump and the drip plugs dilatable to a high degree, or were the system so constructed as to afford the possibility of trapping large quantities of air therein, as when the pump is operated with the reservoir empty, the reliability of operation might be seriously impaired, because the pressure transmitted from the piston stroke, in the former event, would dilate the yielding part of the line, and in the latter compress any trapped air; in either case greatly reducing the pressure at the drip plugs. The trapped air would be compressed further by forcing more oil into the line, in subsequently repeated operations, until the expansive force of the air had risen sufficiently to discharge lubricant through the outlet or outlets of least resistance, through which the relatively large multiple charge that had been forced into the line in the repeated pumping operations, would escape slowly and irregularly. The operation of the system might, moreover, be entirely inhibited if trapped and compressed air could expand into the pump cylinder and maintain the pressure therein in the charging stroke as high or higher than that urging oil from the reservoir.

My construction heretofore described avoids the dilatation of the pipe system, for the entire length thereof being preferably of rigid small-diameter seamless metal tubing, the pressure is reliably transmitted from the piston to the outlet drip plugs as long as the system is completely filled with lubricant, which serves as an incompressible pressure-transmitting agency.

My construction also avoids the objectionable compression of air into the line, for even if the pump were operated with the reservoir empty or substantially empty, the operativeness of the system would not be impaired. In this operation, the piston would be raised through air, in sub-

stantially the same manner as though oil, the valve V being displaced from the piston seat to allow the air to flow freely through the piston. In the return stroke of the piston, however, under the expansive force of the spring 63, the valve V will remain below the piston seat 72, since the air medium has insufficient viscosity to offer the resistance required to raise and seat the valve. The air, therefore, will by-pass freely through the spaces between the valve supporting lugs 80 and through the piston during the downward stroke, and will suffer no compression. The pipe system will thus at all times remain completely filled with lubricant and the possibility of forcing air thereinto by operation from any empty reservoir, is substantially precluded. The operation when repeated after replenishing the reservoir, accordingly proceeds without impairment, and in the manner heretofore described.

Should the oil in the reservoir be at such level that lubricant mixed with air is drawn past the piston in the charging stroke, then, in that event, the air would, thereupon, readily separate above the liquid in the cylinder chamber below the piston, so that in the discharge stroke, such air would escape past the open valve V, after which said valve would close under the resistance due to the viscosity of the oil, all in the manner previously described.

After the operating knob 27 has been drawn outward, it would return but slowly under the slow expansion of spring 63 against the high resistance of the drip plugs, to the ejection of oil from the oil-filled system. Accordingly the operator would merely push the handle back, so that it would be out of the way. In the manual handle return, it will be seen that the tube 125 slides over the plug 128 and the wire 31 therein, the latter being slowly pulled out to its initial position by the slow rotation of the sheave wheel 32 as the cable 101 unwinds from the shaft 86 in the spring return of the piston. In this case, it is preferred to provide the protective tube 134 with a bend or kink as at 143, which resists returning the pulling wire and possibly throwing it off the sheave wheel, were it to be pushed back as a unit with the tube 125.

When the system is originally set up for use, the empty pipe system must first be filled with oil, and the air displaced therefrom. This is accomplished by operating the pump in the normal manner, the oil forced into the pipe system at each pump discharge stroke, advancing therein and displacing the air which escapes through the drip plugs. The pump piston will settle quickly in this operation and substantially with a snap action, the drip plugs offering slight retarding resistance to the escape of the air. By this action, the knob 27 which had been drawn outward in the operation, is snapped back by pull thereon transmitted from the piston through cable 101, shaft 86, sheave wheel 32 and pull wire 31. The operator repeats the pump action, until presently the operating knob 27 does not snap back, but settles slowly, which indicates that the pipe system has been completely filled with oil, and that the drip plugs are exerting their resistance to the passage of oil therethrough.

When after a period of use of the system, the operating knob 27 again is automatically snapped back, after a charging operation, the driver is thereby immediately advised that the system requires attention. In the usual case, this would occur when the reservoir is empty or nearly empty, so that air rather than oil is passed to

the pump cylinder in operation. In the unusual case, this might indicate a fractured or broken pipe line, which would be recognized by the presence of a pool of oil under the vehicle. Thus, my system gives an automatic signal, which unmistakably indicates the need for replenishing the reservoir or repairing a broken pipe line.

In a system in which air could become confined and compressed, it will be apparent that the rapid settling of the pump handle could not be relied upon to indicate the need for replenishing the reservoir, for this settling would occur even with an oil-filled reservoir, if the line trapped air which would easily yield to the discharge of the pump, regardless of the drip plugs at the outlets. Referring again to the pump, the fit of the piston is not particularly tight, and since its normal position is well below the bottom of the tank, any lubricant present in the pump unit will wet the leather cup 80. The pump is thus primed at all times and will operate reliably whenever oil is present.

Moreover, the oil reservoir unit may be placed on the vehicle at any space available therefor, or at any place where filling would be convenient, the operating handle being placed where it is conveniently accessible to the driver. The pump could, for instance, be at the right side of the dash and the handle at the left side of the instrument board, the connecting wire extending across the vehicle and effectively transmitting the operating pull. The reservoir being circular could readily be disposed rotarily within its strap 11 to dispose the sheave wheel in the plane of the pull wire. It will also be seen that the mechanical advantage of the pump could easily be changed by substituting a larger or smaller sheave wheel, as desired or required.

The line filter

The line filter is shown apart from the system in Figs. 7, 8 and 9. It includes a stack comprising filter pads 144¹, 144², etc. alternating with metal separator frames 145^a, 145^b, etc. in superposed relation. Wire mesh separators 146 are interposed between consecutive filter pads and lodged within the corresponding frames 145 to keep the pads from sagging, while permitting free flow of lubricant therethrough. The stack is supported upon an inlet plate 147 which is cut away at the inlet nipple side as at 148. The casing 18 which encloses the filter stack is closed by a cover 149 secured in place by bolts 150, an interposed gasket 151 maintaining the casing oil-tight. The separator frames 145 may be identical stampings, each rectangular in shape, rounded as at 152 and 153 to clear the bolts 150. Each frame has an aperture 154 near one of the corners and a notch 155 near the diagonally opposite corner thereof. Alternate separator frames 145^a, 145^c, 145^e, etc. are disposed with the notches 155 at the right, the intervening frames 145^b, 145^d, etc. being arranged with their notches at the left. The filter pads are perforated near diagonally opposite corners to form bores 156 and 157 through the stack.

In operation, lubricant pressure applied from the pump through inlet nipple 20 is transmitted to the space 148 contiguous to the cover, determined by the lowermost wire mesh separator 160¹, thence through the bore 156 at the left, from which the lubricant passes in parallel through the contiguous notches 155 to the filter pads 144 adjacent to said notches, as best indicated by arrows in Fig. 8. The oil from the pads passes 150

through frame notches 155 at the right side of the stack, as best indicated by arrows, to the outlet bore 157, whence it passes through the space 159 between the stack and the box, determined 5 by the uppermost wire mesh separator 160, for delivery in parallel through the outlet nipples 22, 23, and 24. The flow of lubricant through the various outlet nipples is determined substantially entirely by the resistance of the drip plugs on 10 the corresponding pipe line segments, the nipple 24 which supplies many more drip plugs than nipple 23 in the installation of Fig. 1, passing a proportionately greater proportion of the oil from the filter.

15 The lubricant being admitted at the bottom of the filter and delivered from the top, the air therein when the new installation is set up for use, will naturally be forced to the top as the oil is passed into the filter, and will be swept 20 through the outlet nipples 22, 23, 24 to the pipe line, whence it is vented through the drip plugs, as oil from the pump is forced into the line, until the filter and line are completely charged with lubricant without trapped air. Thereafter, the 25 system operates in substantially the manner previously described, except that the line filter constitutes an additional refinement for removing the minutest particles of dust that may have passed with the oil through the filter 106 in the 30 reservoir. Filter pads 144 being of small area and backed up by wire screen and the casing 18 being rigid, the filter is not subject to objectionable dilatation under the applied pressure, which will, therefore, be effectively transmitted to the 35 drip plugs. It will be seen that the unit described constitutes a combined filter and oil dividing fitting.

The lubricant and pressure source—shown in Figs. 11 and 12

40 In Figs. 11 and 12 is shown an alternative arrangement for avoiding the compression of air into the pipe system. This construction is to be distinguished from that heretofore described in 45 that, where the former by-passes any air otherwise sucked from an empty reservoir before it can enter the line, the latter allows the air to be admitted into the head of the line and then allows ready venting without, however, relieving 50 the pressure upon the lubricant. By this arrangement a reservoir and pump assembly generally similar to that shown in Fig. 2 is provided wherein corresponding parts are designated by the same reference numerals primed however. 55 The reservoir is shown strapped by a band 161 which is drawn at its end by bolts 162 toward a sheet metal support bracket 163 adjacent the reservoir. Each bolt nut 164 is located with a side contiguous to a flat 165 of a depression therefor in the filter bracket whereby the nut is locked. The bracket 163 has tongues 166 bent over against a filter 167 to retain the latter in place therein. The filter may be of any appropriate construction, for instance, that shown in Fig. 13. Integral lugs 168 on the bracket, serve for securing the assembly to the front of the dashboard. A pipe line 169 connects the pump discharge outlet to the inlet 170 of the filter, and an outlet fitting 171 in the filter delivers the oil to the 60 pipe system, which may be similar to that shown in part in Fig. 1. In the present embodiment, the valve V' is devoid of the supporting lugs shown in Fig. 2 and is held upward against seat 72' by a coil-spring s within the cage 76'. It will be seen that although the normal operation on oil in this

case is essentially the same as in the embodiment of Figs. 2 to 5, the spring s would hold the valve V' against its seat in the piston, even should the latter operate on air rather than on oil, so that air pressure would build up in the pipe system, 80 unless obviated by the arrangement now to be described or by some equivalent thereof. Should the pump be operated from an empty cylinder, air forced therefrom into the filter 167 would in the first instance find its way to the 85 top of the filter, rather than to the small pipe line which communicates with the bottom of the filter.

A short connector pipe 172 joints the filter 167 to the reservoir 35' and is attached to the top of the former by a drip plug fitting 173, which may be identical with that shown in Fig. 10. The connector 172 is attached to the top or cover of the reservoir by an elbow fitting 174, although if desired, the two fittings 173, 174 may be interchanged, or drip plugs may be provided at both ends of the connector 172.

Assume that air has become trapped into the filter as by pumping from an empty reservoir. When the pump is again operated, after the 100 reservoir has been replenished, the oil from the cylinder will rise in the filter 167 to eject the trapped air through the drip plug 173, which offers little or no resistance to the passage of air. The ejected air passes through pipe 172 105 into the reservoir 35', whence it escapes through the cover 39'. After the trapped air has thus been removed from the filter, it will be apparent that in the continued discharge of the pump, lubricant will be forced from the drip plug 173 110 and in substantially the same manner and at substantially the same rate as it is forced from each of the other drip plugs on the line to the bearings. The oil from drip plug 173 which does not flow to a bearing, drains back into the reservoir 115 through connector 172 and is thus not wasted. As regards its effect on the lubricant flow, the air venting drip plug is equivalent to the addition of one more drip plug for an additional bearing on the line, which will require a proportionately greater discharge of oil from the pump, the excess charge, as heretofore noted, being, however, in this case returned to the reservoir.

Thus it will be seen that my usual drip plug 125 when used as a venting outlet for any air which would otherwise be trapped, functions as a ready air relief, without permitting the building up of air pressure, while lubricant, by virtue of its high viscosity can be forced through such plug only by a slow drip action and without substantial relief of pressure.

The drip plug when used for air venting and the by-pass valve construction shown in Fig. 2, it will be seen, both operate broadly on the principle of allowing ready escape for fluids of low 135 viscosity, such as air and sustaining the pressure of fluids of high viscosity, such as lubricating oil. Thus, a drip plug may be substituted in the piston in Fig. 2 in lieu of the valve, or a valve of the construction shown in Fig. 2 for the drip 140 plug, in Figs. 11 and 12, although in each case, I prefer the specific construction shown and described.

While I have shown the air venting restriction plug as feeding back into the reservoir from 145 the contiguous filter, it will be understood, of course, that such plug might be located at any place or places in a line, where air would be likely to become trapped, and need not have a return to the reservoir. In such case, it might be desir- 150

able to employ at such places in lieu of the drip plug, a valve construction similar to that shown in Fig. 2, which would prevent the loss of the small amount of lubricant that would, in such arrangement, be wasted by escape from the drip plug or plugs.

While the systems shown in Figs. 1 to 12 have a preferred application to automotive chassis lubrication, it will be understood that the invention is of application broadly to the lubrication from a single source, of machines or mechanical installations, and factory or shop layouts, including line shafting, and that there are various other applications.

15 *The lubricant and pressure source shown in Figs. 13 and 14*

In Figs. 13 and 14 is shown a further alternative form of pump and reservoir. This construction shows a continuous rectangular reservoir 176 which may be of seamless construction, without any soldered parts or bores through which lubricant might leak. The pump and all of the related mechanisms including the oil inlet and the oil outlet are mounted on the cover 177. The flange 178 of the cover is clamped by means (not shown) upon a gasket 179 lodged in the rim of the casing and maintaining the reservoir dust-tight. At one end of the cover 177, I have provided a vertical pressure filter through which the oil is forced in its passage to the line. The filter in this case, comprises a sheet metal box 180 within which are lodged a pair of filter pads 181 and 182 which may be of felt or other appropriate material, and 25 which are securely sustained in spaced relation with respect to each other and to the walls of the enclosing casing by corrugated metal separators, separator 183 resting against the base of the box 180, a pair of similar metal separators 184 and 185 in superposed relation being interposed between the pads 181 and 182 and a fourth separator 186 being superposed over felt 182 to space the latter from the sheet metal cover 187, which is forced into the rim of the box and compresses the contained pads and separators, and is preferably soldered or brazed in place about its rim. At the lower end, an inlet stud 188 extends transversely through the filter and through three superposed washers 189, 190 and 191 interposed between the two filters at this region. The bottom of casing 180 and the cover 187 are preferably dented inward as at 192 and 193 respectively, as shown in the drawings, for secure clamping relation of the parts thereat, the inlet stud 188 being 45 clamped by a nut 194 threaded thereon, against said indented parts 192 and 193. The central washer 190 has a radial bore 195 communicating with the longitudinal bore 196 through the inlet stud to admit the lubricant to opposite sides of the separators 184—185, whence it passes in parallel along and through the two filter pads 181 and 182. A ball check valve 197 may be provided in axial bore 196 and is normally seated by a coil spring 198 reacting against a screw 60 plug 199 closing the outer end of the post.

The filter in its entirety is securely sustained or supported upon the cover flange 178 by means of an outlet stud 200, which extends transversely through the upper end of the filter. The outlet stud, as shown, has a longitudinal outlet duct 201 and radial ducts 202 and 203 communicating therewith respectively from pads 181 and 182. Three washers 204, 205 and 206 about the outlet stud 200 are introduced between the pads 181 and 182, and a pair of washers 207 and 208 about the

outlet stud, are interposed respectively between the base and the cover of the box and the continuous filter pads, said latter washers cut away as at 209 to allow passage for the discharge from the respective filter pads to the radial bores 202 and 203. The outlet stud has a flange 210 with a gasket 211 at opposite faces thereof, resting against the inner side of the reservoir cover flange 178 and the filter bottom 180 and a lock nut 212 threaded upon the outer end of the stud firmly clamps it upon the cover. A similar lock nut 213 is threaded upon the inner end of the stud and compresses the pads and washers between the bottom and the cover of the filter box.

10 The operating pump cylinder 214 is preferably telescoped over and secured upon the inlet stud 188 to extend horizontally near the bottom of the reservoir. For this purpose, the inner end of the cylinder is preferably bent inward to form a flange 215 over a bottoming washer 216, a lock nut 217 threaded upon post 188 clamping flange 215 against filter cover 187 through an interposed compression washer 218. The cylinder 214 has a piston, which comprises a pair of cups 219 and 220 in end to end relation, locked into a 100 unitary structure by a rivet 221, which affords a relatively large central or axial opening through the piston. The rivet is formed in a unitary stamping with a metal lining 222 for the inner of the cups 220 and said lining carries a disk 223 at its inner end to form a cage for the piston valve, which preferably is of the same type as those heretofore described. Briefly, the valve comprises a sheet metal disk 224 with upstanding lugs 225, vellumoid disks 227 and 228 being secured to opposite faces of said disk by a rivet 226. A weak coil spring 230 is disposed within the valve cage reacting against the bottom 223 thereof, and normally urging said valve against the seat 229, which is pressed out from the rivet element 221.

15 The operating means for the pump piston comprises a shaft 231 extending transversely through the cover, above the highest level of lubricant in the casing, thereby dispensing with the need 120 for packing at the bearings. The shaft has at its outer end, a sheave wheel formed of two disks 232 and 233 brazed together, the inner disk 233 having a hub 234 extending over a flange 235 on the bearing 236, to substantially preclude the 125 entry of dust into the reservoir, without, however, frictionally resisting the operation of the sheave wheel. The shaft has secured thereto by means of a transverse bolt 237 an operating cable loop 238 connected to an operating sector 239 upon a 130 transmission shaft 240 well below the upper level of the casing.

20 The rock shaft is preferably of hexagonal or other non-circular stock, rounded at its journal ends 241. The bifurcated or yoke end 242 of a 135 link 243 is keyed upon the shaft 240, the free end of said link being, in turn, connected to a second link 244 which extends into the cylinder 214 and is pinned as at 245 to the piston. The piston, as shown, is midway between the two sides of the 140 casing and a pair of identical coil springs 246 and 247 are preferably provided to urge the piston to the discharged position shown in Fig. 13. The coil springs are hooked to the casing at their inner ends as at 248 and at their outer ends at notches 145 249 in yoke arms 250, which are keyed over the rock shaft 240, to rotate as a unit therewith.

25 To avoid the need for perforating the reservoir wall in order to form a bearing for the rock shaft 240, I preferably provide a separate support frame 150

comprising an end wall 251 extending vertically downward from the cover and having an aperture 252 to clear the nut 213 of the outlet post, but clamped as at 253 between the pump cylinder 214 and the nut 194 through interposed gaskets 218 and 254. The support frame has lateral wings 255 and 256 which may be and preferably are secured by rivets (not shown) to the reservoir cover, said wings extending, when the cover is applied, with little clearance, as shown, parallel to the lateral walls of the casing and having the apertures 257 to provide the bearings for the rock shaft. The support frame may also provide added bearing length for the operating shaft 231 which extends therethrough, as shown.

By the construction described, with the filter 258 at the right end of the rectangular reservoir and the operating rock shaft near the opposite end of the rectangular casing, a substantial space 20 is provided therebetween to accommodate a filter 258 of substantial area, which is desirable as the lubricant poured into the reservoir, might seep too slowly through a small area filter of texture sufficiently close to be effective. The filling cup, 25 as shown, is a cylindrical can 259 with a peripheral bead 260, resting upon a collar 261, in turn, lodged in a corresponding aperture in the reservoir cover. Strainer cup 262 which may be of copper mesh is supported from a metal annulus 263 mounted at the rim of the filling cup 259. The filling cup has a neck 264 fitted thereover and is provided with a hinged cap 265 similar to that shown and described in connection with Fig. 2. The bottom 266 is corrugated and is crimped and soldered to the side wall of the cup at 269. A removable corrugated sheet metal cap 268 presses the filter pad 258 against the bottom 266. Cap 268 has a reversely turned flange 270 telescoped over the rim of the bottom 266 and secured thereto by a releasable snap lug 271. The corrugations are provided with perforations 269, to admit lubricant to filter pad 258 and to drain it therefrom into the reservoir therebelow.

In operation, the reservoir being assumed to have lubricant therein, at least to a level to cover the horizontal pump cylinder 214, the sheave wheel 232—233 is rotated by tension applied to the pull chain or wire (not shown). Cable 238 will, therefore, wind around the rotating shaft 231, moving the sector 239 in clockwise direction, to correspondingly rotate the rock shaft 240, until the operating handle, which may be similar to that shown in Fig. 6 reaches the end of its stroke. In this operation, lever 243 is rotated with the rock shaft and through link 244 draws the pump piston outward, the valve thereof by reason of the vacuum, unseating against the resistance of the coil spring 230, to admit lubricant through the relatively large low-resistance rivet aperture 221, into the inner end of the cylinder. During this operation, the levers 250 move with the rock shaft and the springs 246 and 247 are tensioned.

When the operating handle is now let go, the return or contraction of the springs 246 and 247 draws the levers 250 in counterclockwise direction to correspondingly rotate the rock shaft 240 and to press the pump piston inward through the lever 243 and link 244 to feed the pump charge to the line. During the discharge stroke, the piston valve remains closed against its seat 229 to urge the lubricant through the bore 196 of the inlet post, opening the ball check valve 197, whence the lubricant is forced through radial passage 195 laterally of the separators 184—185,

upward through the two filter pads 181 and 182, in parallel, whence it escapes through notches 209 in parallel and through the radial ducts 202 and 203 in the outlet post to the longitudinal duct 201, from which it proceeds through the pipe system to the various drip plugs or other outlets in the manner heretofore described.

In the charging operation, it will be seen that at the outset, the spring hooking ends 249 of the levers 250 move substantially in the direction of elongation of the springs 246—247 and as the stroke proceeds, at a progressively increasing angle with respect thereto, so that the mechanical advantage of the transmission between the sheave wheel and the springs increases, as the charging stroke is performed, thus compensating for the tensioning of the spring. It follows that the manual force applied for operating the pump will remain substantially constant throughout the stroke and the need for added effort toward the end of the stroke, is avoided.

Similarly during the discharge operation, the spring is at its maximum tension at the beginning of the discharge stroke, while the mechanical advantage of the application of its tensile force to the rock shaft is a minimum, and progressively increases as the contraction proceeds, to compensate for the diminishing tension of the springs, thereby assuring a substantially uniform high pressure upon the piston throughout the stroke.

In order to prevent the cable 238 from becoming slack during the return operation and possibly slipping off the arcuate sector surface, I provide a relatively weak coil spring 272 encircling the operating shaft 231 and anchored at one end 273 to an inwardly projecting finger 274 in the casing cover. At the other end, spring 272 presses against a finger 275 projecting from a sleeve 276, which encircles the operating shaft 231 and is pinned thereto by bolt 237, as shown. The coil spring 272 is tensioned in a direction opposite to that in which the shaft 231 is rotated, in charging the pump, so that it will unwind partly in the charging stroke. It follows that during the pump discharge, the spring 272 exerts a rotary impulse upon the shaft 231 to keep the cable 238 taut, as it is overcome by the more powerful springs 246 and 247, which in the discharge stroke, return the sector 239 to the position shown in Fig. 13.

In the present embodiment, I have shown a tongue 277 struck down from the end of sleeve 276 and tongues 278 and 279 struck in from the support frame in the path of tongue 277, act as stops to limit the range of rotation of the operating shaft.

The line filter, in the present as in the embodiments of Figs. 1, 7, 8, 9 and 12 is effective to remove substantially the finest particles of dust that may have passed with the oil through the filling filter. The line filter thus provides a high degree of refinement, avoiding the gradual accumulation of dust at the drip plugs in prolonged use of the system. It is found in practice, however, that the various systems disclosed operate satisfactorily for long periods, even in the absence of the line filter.

The pressure and lubricant source or pump of Figs. 13 and 14 is shown devoid of special means to prevent the compression of air into the line upon operation from an empty reservoir. In practice, unless all of the air is specially with-

drawn from the filter when the system is set up for use, and unless the draining of the reservoir to a level below the top of the pump cylinder is at all times guarded against, difficulties might ensue in operation in the absence of some safeguard, such as shown in Figs. 1 to 12.

It is obvious that the lubricating installations disclosed in the present invention may be used in connection with mechanisms other than automobile chassis. The flow controlling or metering outlets of the lubricating installations to which this invention is particularly applicable may be of the type set forth in my copending applications Serial No. 580,668, filed August 9, 1922, Serial No. 596,856, filed October 25, 1922, and Serial No. 695,740, filed February 28, 1924, as well as in my Patents Nos. 1,632,771, 1,732,212 and 1,746,139. The lubricating installations may also be specifically actuated as disclosed in said copending applications and patents.

I claim:—

1. In a lubricating installation, in combination, a pump having a cylinder and a discharge outlet, a piston therein for pressure discharge of lubricant, a valve in said pump, closed during discharge action by the pressure exerted thereon due to the viscosity of the lubricant in order to sustain the discharge pressure, whereby in case air is admitted to the cylinder, the viscosity will be insufficient to seat said valve and the air will not be forced through the lubricant discharge outlet.

2. In a lubricating installation, in combination, a pump cylinder, a piston therein, a valve cage carried by said piston, a disk valve in said cage having spacer lugs to sustain the valve between the bottom and the top of the cage during the up stroke of the piston for by-passing lubricant through the piston and constructed and arranged to be seated in the down stroke of the piston by reason of the viscosity of the lubricant medium, and to remain at the bottom of the cage when the piston is operating on air.

3. In a lubricating installation, in combination, a piping system having a plurality of outlets to bearings to be lubricated, pressure operated valves maintaining said system charged with lubricant, a lubricant reservoir, a cylinder supplied therefrom and communicating with said pipe line, a plunger in said cylinder, for applying pressure to the system, said plunger having a valve pressed closed during the operating stroke of the plunger upon lubricant, and remaining open in plunger operation upon any air entering into the path of the piston.

4. In a pump, in combination, a cylinder, a piston therein having a valve seat, a valve cage and a disk valve gravity-seated upon the bottom of said cage to afford relatively free passage for fluid during the upstroke of the piston and serving by the viscosity of the liquid medium to close said piston during the down stroke thereof, said valve remaining in its lowermost position away from said seat in the down stroke upon an air medium.

5. In a liquid pump, in combination, a cylinder, a piston therein having a valve seat, a disk valve and a cage for said valve carried by said piston, said cylinder having a valve seat over which said cage is telescoped, to maintain said valve pressed against both said seats, said valve having supporting lugs, whereby upon the up stroke of said piston, the valve will be raised by the rise of said cage from said second seat and

will be maintained out of seating relation with respect to the piston.

6. In a lubricating installation, in combination, a pressure chamber, an operating member therein for discharging lubricant therefrom through a restricted outlet, a valve near the top of said pressure chamber and closing the same during the discharge operation under the pressure applied thereto by reason of the viscosity of the lubricant medium, whereby any air admitted with lubricant to the pressure chamber would readily separate to the top thereof and escape through said valve during the compression stroke.

7. In a lubricating installation, in combination, a pump cylinder, a piston therein, a pipe system supplied from said cylinder and having a plurality of outlets for escape of lubricant to bearings, means in advance of said outlets, determining the distribution of the lubricant supplied from the pump, a vertical filter in the line to intercept any solid particles carried by the lubricant, said filter having an outlet to permit escape of any air trapped therein, said outlet constructed and arranged to sustain the pressure on the viscous lubricant.

8. In a lubricating installation, in combination, a pump, a pipe system supplied therefrom having a plurality of outlets to bearings, devices controlling the supply to each of the bearings when pressure is supplied to the line, means maintaining the line normally filled with lubricant in advance of said devices, and an air vent at about or above pump level and at a part of the pipe line where air might become trapped, said vent highly restricted to resist relief of lubricant pressure thereat.

9. In a lubricating installation, in combination, a reservoir, a pump supplied therefrom, a filter connected to receive the discharge from said pump, a pipe system supplied from said filter, said system having a plurality of outlets for simultaneous delivery to a plurality of bearings, means maintaining said system normally filled with lubricant, a return flow passage from the top of said filter directly to the top of said reservoir, said passage having impedance therein affording high resistance to the flow of the viscous lubricant to sustain the pressure on the system, while affording ready escape for any air trapped in the filter.

10. In a lubricating installation, in combination, a lubricant reservoir, a pump contiguous thereto and supplied therefrom, a plunger in said pump, a filter arranged vertically adjacent said reservoir and receiving the discharge from said cylinder, a pipe system connected to said filter and having a plurality of outlets to bearings, high resistance drip elements in advance of the bearings, to determine the distribution of the lubricant charge thereto, means preventing escape of lubricant from the pipe system when the pump is not operating, a return pipe from the top of the filter to the reservoir, and a high resistance drip element in said return pipe to allow ready escape therethrough of any air trapped in the filter, and sustaining lubricant pressure on the line.

11. A lubricant supply installation for a central chassis lubricating system, said installation comprising a pump having a casing in inobtrusive position in front of the dash, a spring discharged pump plunger in said casing, a rock shaft extending through said casing, a pull handle for said pump accessible from the driver's seat, a flexible tension member connected between said handle and the exposed part of said rock shaft, and a

flexible member within said casing connecting said plunger and said rock shaft.

12. An operating handle for a lubricating system comprising a cylindrical casing, inclined with respect to the vertical, a rod slidably disposed within said casing and having a protruding handle end, a stop at the inner end of said rod, and a stop pin adjustably mounted on said casing to limit the stroke of said handle for correspondingly predetermining the charge of the pump actuated thereby.

13. An operating handle for a pump comprising a cylindrical casing, a tube therein having a stop cap at its inner end, a plug slidable within said tube and normally maintained against said cap, a tension member secured to said plug for connection to the pump, said casing having a collar thereon in adjustable position, and a pin through said collar serving as an adjustable stop for said cap to predetermine the length of stroke.

14. In a lubricating installation, in combination, a pump, a readily accessible operating handle therefor having a plunger rod, a wire drawn by said rod to charge the pump, a protective sleeve for said wire, spring means discharging said pump, said sleeve being offset from a straight line, to frictionally resist movement of the wire, whereby the wire will be restrained by the offset in the manual return of the operating handle and will be pulled through the offset as the pump is discharged.

15. An oil pressure generator for lubricating installations comprising a reservoir, an operating cylinder mounted in said reservoir and having a wide inlet near the bottom of the latter for ready entry of lubricant into said cylinder, a plunger in said cylinder, and operating means therefor projecting from said reservoir at a level above the highest point of lubricant therein, said reservoir having a filling cap, a large-area strainer therebelow for intercepting solid particles admitted with the lubricant, and a filter in said reservoir in the path of lubricant flow between said strainer and the cylinder outlet.

16. In apparatus of the character described, in combination, a reservoir, a cylinder extending longitudinally through said reservoir, a filling opening at the top of said reservoir, large-area, low-resistance openings in said cylinder and near the bottom of said reservoir for admission of lubricant to the latter, said cylinder having an outlet near the bottom thereof, a piston in said cylinder, a horizontal operating shaft above said piston, and a cable connecting said shaft and said piston.

17. Apparatus of the character described comprising a reservoir having a cover, a strainer and a cylinder in side by side relation and extending longitudinally within said reservoir, a filling cap in said cover above said strainer, a plunger in said cylinder, a horizontal operating shaft for said plunger above said cylinder, said cylinder having an outlet near the bottom thereof, a cable through said cylinder connecting said operating shaft to said piston, and large-area low-resistance lubricant inlet apertures in said cylinder near the bottom of said reservoir.

18. In a pressure generator for lubricating installations, in combination, a lubricant reservoir having a removable cover, a pump cylinder extending longitudinally through corresponding apertures in the base and in the cover of said reservoir and rigidly fitted therein and projecting below the base of the reservoir, a plunger within said cylinder, a spring within said cylinder nor-

mally seating said plunger at the bottom of said cylinder, wide inlet openings in said cylinder near the bottom of said reservoir, and operating means for said plunger extending longitudinally through said cylinder, said plunger having a valve through which the lubricant above said plunger passes on the up stroke thereof, and automatically closing during discharge.

19. In a pump, in combination, a cylinder, a piston therein, charging means comprising a transverse shaft above said cylinder, a cable connecting said shaft to said piston, the axis of said shaft being offset from the axial plane of said cylinder, so that the connecting cable about said shaft will extend to said piston axially of said cylinder, and spring means to discharge the pump.

20. In apparatus of the character described, in combination, a lubricant reservoir, a pump cylinder communicating with the lower part of said reservoir, a filter pad near the lower part of said reservoir above the communicating area, and open sustaining means between the bottom of said reservoir and the surface area of said filter.

21. The combination set forth in claim 20 in which the spacer means for the filter pad comprises a flexible metal band wound about said cylinder and resting upon the bottom of the reservoir, and supporting the felt upon its upper convoluted edge.

22. In apparatus of the character described, in combination, a reservoir having a filling opening, a strainer bag mounted therebelow, a pump cylinder extending vertically through corresponding apertures in the base and cover of the reservoir laterally of the filter and protruding below the bottom of the reservoir, a piston within the cylinder, spring means urging said piston to seating relation, inlet openings of large size in said cylinder near the bottom of the reservoir, tension means attached to said piston and extending longitudinally through said cylinder and through said spring for drawing the piston upward to charge the cylinder, a filter in said reservoir above said inlet openings, and a support retaining said filter against sagging, said support affording space between said filter and the bottom of said reservoir for a filtered supply of lubricant for the cylinder.

23. In apparatus of the character described, in combination, a reservoir, a cover therefor, pump operating means extending through said cover, a pump discharge fitting extending through said cover, a filter carried by said cover and extending downward therefrom, a pump cylinder carried by said filter and having an inlet near the bottom of said reservoir, an operating piston in said cylinder, and transmission means in the reservoir between said operating means and said piston.

24. In apparatus of the character described, in combination, a rectangular reservoir, a cover therefor, an operating member extending from said cover near one end of the reservoir, an outlet fitting extending from said cover near the opposite end of the reservoir, a filter member carried by said outlet fitting and extending downward therefrom to near the bottom of the reservoir, a pump cylinder carried by the lower end of said filter and extending horizontally toward the opposite wall of the reservoir, a piston in said cylinder, a filling strainer cup of relatively large area fitted into the cover of said reservoir, between said filter and said operating

shaft, and transmission means clearing said filter cup and connecting the operating shaft to said piston.

25. In apparatus of the character described, in combination, an imperforate rectangular reservoir, a flanged cover therefor extending above the reservoir, a pump near the bottom of said reservoir, horizontal operating and transmission shafts for said pump, vertical carrier means mounted on said cover and fitting in proximity to the lateral walls of the reservoir and serving as bearings for the shafts below the rim of the reservoir.

26. A lubricant pump comprising a rectangular reservoir, a flanged cover therefor, a support frame on said cover extending downward therefrom and having wings in close proximity to the lateral walls of the reservoir, a horizontal pump cylinder mounted upon the lower end of said support frame and extending near the bottom of the reservoir, a piston in said cylinder, an operating shaft through said cover, and transmission means between said shaft and said piston and including a rock shaft journaled below said cover in the wings of said support frame.

27. Apparatus of the character described, including a reservoir, a horizontal cylinder near the bottom of the reservoir having a piston, and operating shaft for said piston through said cover, transmission means between said shaft and said piston including a rock shaft, a sector rotatable therewith, a strap connecting said sector and said operating shaft, linkage between said rock shaft and said piston, and a pair of coil springs symmetrically arranged at opposite sides of said cylinder and anchored with respect to said rock shaft to discharge said cylinder under pressure transmitted from said rock shaft through said linkage.

28. In a pump, in combination, a rectangular reservoir tank, a flanged cover therefor, a support frame secured to said cover and having a vertical end wall, and lateral wings extending in contiguity to the lateral walls of the reservoir, an operating shaft through said cover, a rock shaft below said cover journaled in said wings, a filter secured against one side of said support frame end wall, between said wall and the contiguous end of the casing, a pump cylinder secured with respect to the bottom of said wall and extending horizontally near the bottom of said reservoir, a sector on said rock shaft, a strap connecting said operating shaft to said sector, linkage actuated by said rock shaft, connecting the latter to the piston, a pair of springs symmetrically arranged with respect to said piston, and arms on said rock shaft connected to said springs.

60 29. An operating means for a pump comprising an operating shaft, a transmission including a rock shaft, a sector on said rock shaft operatively connected to a pump, a strap connecting said operating shaft and said sector, and spring means to maintain said strap taut during the return of the sector after operation of the shaft.

30. A pump comprising a cylinder, an ejector therein, a spring normally urging said ejector to discharge position, pump operating means including a rock shaft, a sector on said rock shaft operatively connected to one end of said spring, a flexible tension member extending about said sector, and spring means to maintain said tension member taut during the spring return of the sector in pump discharge.

31. A lubricating device comprising a reservoir including an imperforate cup-shaped base for storing lubricant and a cover therefor, and a reciprocating pump, a horizontally pivoted actuator for said pump, a connecting link therebetween, resilient means also therebetween alternately stressed and released by said actuator, an inlet opening for said reservoir, a lubricant strainer, and a pump outlet all supported on or from said cover, the pump being positioned lowest with a pump inlet adjacent the bottom of the base. 80 85

32. A reservoir and pump unit comprising an imperforate open receptacle devoid of mechanism, a cover removable with respect thereto, a pump element carried by said cover and completely submerged in said receptacle, pump operating means carried by said cover and a spring fixed at one end by said cover and at the other attached to the pump operating means normally retaining said operating means in a definite position. 90 95

33. A supply installation for a central lubricating system comprising a unitary imperforate reservoir having an open rim, a cover therefor, a pressure pump mechanism including operating means therefor carried by said cover, said pump having an inlet near the bottom of said reservoir, means conveying the discharge of said pump upward to said cover, and a coil spring fixed at one end by said cover and at the other attached to the pump operating means maintaining said operating member in position. 100 105

34. A lubricant pump and reservoir combination comprising a reservoir, a pump adjacent to the bottom of said reservoir, an actuating arrangement for said pump attached to the top of said reservoir, a cylinder extending through said reservoir from said actuating arrangement to and in communication with said pump, actuating connections from said arrangement to said pump extending downwardly through said cylinder, openings in said cylinder adjacent the bottom of said reservoir and lubricant cleansing means associated with said openings whereby said cylinder will serve to contain a supply of cleansed lubricant for the pump. 110 115 120

35. A lubricant pump and reservoir combination comprising a main reservoir, a subsidiary reservoir, a strainer arrangement through which communication is established between the main reservoir and the subsidiary, a pump positioned adjacent the bottom of said reservoirs and in direct communication with said subsidiary reservoir, an actuator for said pump attached to the top of said reservoir and actuating connections from said actuator to said pump extending downwardly through said subsidiary reservoir. 125 130

36. A lubricant supply installation comprising an imperforate reservoir devoid of mechanism, a flanged cover therefor, a pump cylinder having its inlet and its outlet both near the bottom of said reservoir, means suspending said cylinder from said cover, dirt intercepting means carried by said pump suspending means, a reciprocating plunger in said cylinder, means conveying the discharge of said pump upward, an outlet nipple through the flange of said cover for connection to the distributing system, and operating means for said pump including a rock- 135 140 145 150 ing element at said cover and a pump operating transmission connecting said element with respect to said pump plunger and also carried by said cover, said operating means and operating transmission being connected with coil spring 150

- means, which coil spring means is fixed at one end in respect to the rocking element and extends from the rocking element along the transmission toward the pump plunger, the axis of 5 said coil spring means extending in the same direction as said cylinder, the end of said coil spring means removed from said rocking element being fixed in respect to said cylinder. 37. A lubricating device including a reservoir 10 with a cup-shaped enclosure and a cover member therefor, a filler opening in said cover member, an outlet in said cover member, a reciprocating pump including piston and cylinder elements suspended from said cover member, having an outlet 15 connection to said outlet in the cover member and positioned adjacent the bottom of the reservoir and an actuating mechanism for said pump supported by said cover comprising a reciprocating member, a horizontal pivotal axis member there- 20 for, extensions from the cover supporting said axis member at the ends, coil spring means fixed at one end in respect to the reciprocating mem- 25 ber and at the other end in respect to the cover and axially extending generally toward and to one side of said pump, and means simultaneously 30 to actuate the piston of said pump in one direction and stress said spring means, whereby said spring means upon return to unstressed condition will tend to actuate the piston of said pump in a reverse direction. 38. A lubricating device including a reservoir with a cup-shaped enclosure and a cover member therefor, a filler opening in said cover member, an outlet in said cover member, a reciprocating 35 pump including piston and cylinder elements, suspended from said cover member, having an outlet connection to said outlet in the cover member and positioned adjacent the bottom of the reservoir and an actuating mechanism for said 40 pump supported by said cover comprising a re- ciprocating member, a horizontal pivotal axis member therefor, extensions from the cover sup- porting said axis member at the ends, coil spring 45 means fixed at one end in respect to the recipro- cating member and at the other end in respect to the cover and axially extending generally to- 50 ward and to one side of said pump, and means simultaneously to actuate the piston of said pump in one direction and stress said spring means, 55 whereby said spring means upon return to un- stressed condition will tend to actuate the piston of said pump in a reverse direction, said spring means being elongated upon a charging move- ment of said piston and being decreased in length upon a subsequent discharging movement. 39. A lubricant supply installation for a cen- tral lubricating system comprising a reservoir having an imperforate bottom and side wall and an open rim, a cover therefor, a pump, a pump carrying means depending from said cover, said pump having inlet and outlet port means, the former at the bottom of the reservoir and the latter leading through the cover, said pump carrying means including a strainer positioned closely adjacent said port means to assure the supply of clean oil to said system, a reciprocating actuating means for said pump, a support for said means extending from said cover, and coil spring means axially directed downwardly toward said pump for biasing said actuating means, said coil spring means being fixed at one end in respect to said cover and at the other end in respect to said actuating means. 40. A lubricant supply installation for a cen- tral lubricating system comprising a reservoir having an imperforate bottom and side walls and an open rim, a cover therefor, a pump plunger and a pump cylinder both carried by said cover, the pump cylinder being rigidly attached to said cover and the pump plunger being movable in respect to said cover, said pump cylinder being 100 positioned adjacent to the bottom of the reservoir and having its inlet near the bottom of said reservoir and having an outlet through said cover, a strainer attached to said cylinder to assure the entry of clean oil to said system, and reciprocat- 105 ing actuating means for said pump carried by said cover, a support for said means extending from said cover, and coil spring means axially directed downwardly toward said pump for biasing said actuating means, said coil spring means 110 being fixed at one end in respect to said cover and at the other end in respect to said actuating means. 41. A lubricant supply installation for a cen- tral lubricating system comprising a reservoir 115 having an imperforate bottom and side wall and an open rim, a cover therefor, a pump, a pump carrying means depending from said cover, said pump having inlet and outlet port means, the former at the bottom of the reservoir and the lat- 120 ter leading through the cover, said pump carrying means including a strainer located closely ad- jacent to said port means to assure the supply of clean oil to said system, and also carrying a re- ciprocating actuating arrangement extending 125 downwardly from the cover which actuating ar- rangement comprises a coil spring fixed in re- 130 spect to the actuating means at one end and to the cover at the other end, said spring tending to cause a return reciprocation of said pump.
